UNITED STATES PATENT OFFICE.

CHARLES EDWARD HAVILAND, OF LIMOGES, FRANCE.

DESIGN FOR A PLATE.

SPECIFICATION forming part of Design No. 21,684, dated July 5, 1892.

Application filed June 7, 1892. Serial No. 435,895. Term of patent 14 years.

To all whom it may concern:

Be it known that I, CHARLES EDWARD HAVILAND, a citizen of the United States, residing at the city of Limoges, in the Republic of France, have invented and produced a new and original Design for a Plate and other Articles, of which the following is a specification, reference being had to the accompanying drawings, forming part thereof, and in which—

Figure 1 is a top view of a plate bearing my design; Fig. 2, a detached section of same on the dotted line 2 2 of Fig. 1, and Fig. 3 a detached section of same on the dotted line 3 3 of Fig. 1.

The leading features of my design consist of the shape of the rim of the plate and the

ornamental configuration along the edge thereof, as shown in Fig. 1. The rim of the plate is composed of the sections A, having 20 the concave edges B and separated by the scalloped sections C, and upon the edge of this rim are the conventionalized foliate scrolls D, appearing at each of the concave edges B, as illustrated in Figs. 1 and 3. 25

What I claim is—

The design for a plate or other article, substantially as shown and described.

Signed at the city of Limoges, in the Republic of France, this 25th day of May, 1892. 30

CHARLES EDWARD HAVILAND.
